DESIGN FOR A FLUORESCENT FLOOR LAMP

John F. Livers, Decatur, Ill., assignor to Faries Manufacturing Company, Decatur, Ill., a corporation of Illinois

Application September 28, 1940, Serial No. 95,479

Term of patent 3½ years

To all whom it may concern:

Be it known that I, John F. Livers, a citizen of the United States, residing at Decatur, in the county of Macon and State of Illinois, have invented a new, original, and ornamental Design for a Fluorescent Floor Lamp, of which the following is a specification, reference being had to the accompanying drawing, forming part thereof, in which—

Fig. 1 is a perspective view of the fluorescent floor lamp showing my new design; and

Fig. 2 is a cross-section taken on the line 2—2 in Fig. 1, in the direction indicated by the arrows.

I claim:

The ornamental design for a fluorescent floor lamp, as shown.

JOHN F. LIVERS.
